UNITED STATES PATENT OFFICE

WILLIAM CALVANO, OF NEW YORK, N. Y.

COLLAPSIBLE BED

Application filed May 9, 1927, Serial No. 189,916. Renewed October 23, 1929.

This invention relates to beds and more particularly to beds of a folding or collapsible type.

It is a major purpose of the present invention to provide in a "regular bed"—as differentiated from the so-called "folding bed"—such structure as will permit of the ready and convenient shipping of the bed in collapsed form.

10 It is a further object of the present invention to provide a bed of the class described in which all parts, i. e. the bed-spring, the bed-spring frame and the bedstead are unitary. It is a still further object of the invention to provide a bed which may be readily collapsed to permit movement of the bed for cleaning under or adjacent thereto, or for any other purposes.

In the various types of "regular beds" as 20 at present manufactured wherein the bed-spring, the rails and the bedstead proper are separate elements, it is comparatively difficult and a fairly considerable amount of effort or labor is required when it is desired 25 to move or take down the bed. The spring must first be removed and the rails then withdrawn from the usual sockets or brackets upon the bedstead or bed posts. The normal weight of the springs and rails and the size 30 thereof is such as to render it extremely difficult for the housewife to either assemble or take down a bed without assistance, or move the same.

In the shipping of beds of this type, or in 35 the movement of the bed as upon a change of address, the size of the spring and the length of the rails renders such shipping or movement inconvenient. At times, through such movement or shipping, loss of a rail or 40 other part will occur, and as a result the bed will be rendered useless until such missing part is replaced.

Another object of the present invention is 45 the provision of a bed in which the structure is unitary so that after assembly thereof the bed may be collapsed for moving, shipping, storing or any other purpose, without any disassembly of parts. To this end the bed-spring and bed-spring frame or rails are so 50 constructed as to permit a collapsing thereof

substantially within the height of the bedstead proper.

It is a further object of the present invention to provide an arrangement of parts resulting in the provision of a pocket or recess adjacent the foot of the bed for the convenient reception of the blankets, comforts, sheets or other covering, on the bed together with the bed-spread, thereby eliminating any necessity for a particular conformation or 60 folding of such coverings.

It is a further object of the invention to provide a novel bed-spring supporting element for the additional support of the bed-spring upon depression thereof when the bed 65 is in use.

It is a still further object of the invention to provide a bed which will be strong and durable, which will be simple in operation, 70 easily constructed and which may be economically manufactured. It is a further object of this invention to provide in a bed of the class described a novel bed-spring and bed-spring frame, novel connections between the frame and bed posts, and novel means for 75 securely locking and retaining the bed in set position. Further objects of the invention will be hereinafter more fully set forth.

The accompanying drawings illustrate one 80 practical bed embodying the present invention which will be described in detail to enable others to understand and use the same, but it is to be understood that the invention is not restricted to the specific construction shown in the drawings and herein described. 85 The invention, accordingly, consists in the features of construction, the combination of elements and arrangement of parts which will be exemplified in the construction herein-after set forth and the scope of the application thereof will be indicated in the following claims.

As shown in the drawings:

Figure 1 is a side elevational view of the 90 complete bed, illustrating the same in set-up position.

Fig. 2 is a top plan view of the complete 95 bed, illustrating the same in set-up position.

Fig. 3 is a side elevational view of the com- 100

plete bed, illustrating the same in collapsed position.

Fig. 4 is a fragmentary enlarged detail view of one of the bed-spring retaining brackets.

Fig. 5 is a detail sectional view taken on the line 5—5 of Fig. 4.

Fig. 6 is a detail sectional view taken on the line 6—6 of Fig. 4.

Fig. 7 is a detail sectional view taken on the line 7—7 of Fig. 1, illustrating the bed-spring supporting member.

Fig. 8 is a fragmentary enlarged detail view of one of the bed-spring frame retaining brackets, illustrating a modified form of locking element for retaining the bed-spring frame in set-up position.

Fig. 9 is a detail sectional view taken on the line 8—8 of Fig. 8.

Fig. 10 is a view similar to Fig. 8 illustrating a still further modified form of locking element.

Fig. 11 is a detail view of the locking element illustrated in Fig. 10, detached.

As shown in the drawings, the novel unitary bed comprises a head member H, a foot member F, and a spring member S. The spring member is designed to be mounted upon brackets 1 rigidly secured to the head and foot members as will be hereinafter more fully described. The head and foot members may be of any desired size, conformation and material.

While the bed spring S may be of any type that will permit of the desired collapsibility, a preferred embodiment thereof has been illustrated in the drawings, the spring comprising a plurality of plates 2 resiliently secured or mounted within the spring frame member 3. The frame 3 is preferably formed of angle iron having an upstanding flange 3^a and an inwardly directed flange 3^b—thus providing a proper seat for the mattress (not shown). Reinforcing corner plates, rectangular in shape, suitably secured to the frame member as by welding or the like, may be provided to strengthen the same.

The plates 2 are provided with a series of apertures 2^a adjacent the edges thereof for the reception of one end 4^a of a coil spring or other resilient element 4. In like manner the flange 3^b of the frame member is similarly provided with a series of apertures 3^a in proper alinement with the apertures 2^a, and adapted to receive the other end 4^a of such springs. The adjacent innermost edges of the plates 2 are fastened together by similar resilient elements or coil springs 4. Each plate 2 is further provided with a plurality of relatively large spaced apertures 2^b for purposes of ventilation.

While only two of such plates have been illustrated, it will be readily seen that any desired number thereof might be as conveniently used. Any desired material might be

used in the manufacture of the plates 2, as for example, relatively thin sheet steel.

To permit of collapsibility of the spring frame, the longitudinal portions thereof are formed in two sections, hingedly secured to each other as shown at 3^c in the drawings.

To further assist in the support of the spring proper when the bed is in use, a substantially U-shaped member or rod 3^d is provided, see Fig. 7 of the drawings, the ends 3^e thereof being turned outwardly and being adapted to form hinge pins for the connections 3^c. It will be readily understood that upon sufficient depression of the bed spring, the spring will rest upon and be supported by the member 3^d. In actual practice it has been found that the lower level of this supporting member need be but approximately three inches below the spring proper in order to properly support the said spring when depressed. The positioning of this member it will be noted will permit it to lie between the plates 2 when the bed is collapsed or folded. It will be noted that the hinged connections 3^c are in alinement with the resilient connection between the plates 2, so as not in any way to interfere with the collapsibility of the entire spring and frame member.

The brackets 1 are adapted to be rigidly secured to the head and foot members as by rivets 1^b or any other suitable means passing through turned flanges 1^a on the said brackets. Each portion of the bed-spring frame 3 has a sliding pivotal connection with the adjacent bracket as by bolts, rivets or the like 3^c, rigidly secured to the upstanding longitudinal flanges of the spring frame, and adapted to travel within horizontally disposed slots 1^c provided in the brackets. Each bracket is further provided with an angularly disposed cross slot 1^d extending from the upper edge of the bracket to the slot 1^c for the ready assembly or connection of the frame and brackets.

Washers 3^e are provided upon the members 3^c adjacent the head member of the bed, the washers being positioned between the spring frame and the brackets 1. It will thus be readily understood that the brackets secured to the head member are spaced apart a slightly greater distance than the brackets secured to the foot member, thereby permitting the brackets upon the head member to lie in overlapping relationship, when the bed is collapsed or in folded position, with respect to the adjacent brackets upon the foot member, see Fig. 3 of the drawings, to permit of the more snug folding or collapsing of the structure. The provision of a slotted pivotal connection between the spring frame and the brackets permits the pivotal members 3^c to move backward within the slots 1^c when the bed is collapsed thereby materially reducing the height of the top of the spring

and frame when in such collapsed position. With this arrangement of parts the level of the top of the spring, it will be noted, will be conveniently beneath the top of the head member of the bed.

The flanges 1^a of the brackets are less in height than the face portions of the said brackets, thereby providing a space between the upper portions of the brackets and the head and foot members of the bed. The flanges on the rear brackets, adjacent the foot members, it will be noted are materially lower than the flanges of the front brackets, thereby creating a substantial pocket 1^f between the foot member of the bed and the spring-frame. This pocket provides a space for the convenient reception of the blankets, comforts, sheets or other covering on the bed together with the bed-spread, thereby eliminating any necessity for the particular conformation of such coverings. It is well known in the art that the majority of bed-spreads as at present manufactured have their bottom corners cut away to permit the bed-spread to neatly hang between the foot member of the bed and the mattress thereof. With the above described arrangement it will be readily seen that the necessity for any such cutting away or other particular conformation is obviated. In actual practice it has been found that the provision of a pocket or space of from one to two inches is more than ample for this purpose.

Each bracket 1 is provided at its upper outer corner with inturned horizontal and vertical flanges 1^g and 1^h respectively, adapted to snugly fit the corner of the spring frame member 3, and thereby securely retain such frame member in set-up position and prevent any undesired collapsing or movement thereof.

Any desired locking means may be provided to retain the spring frame in set-up position. As shown in the drawings, more particularly Figs. 4 and 5 thereof, a preferred embodiment of locking means comprises a spring member 5 having an inwardly directed shoulder 5^k adapted to project through an aperture 1^k in the bracket 1, the shoulder 5^k lying directly beneath the plate of the bottom flange 3^b of the spring-frame member. It will be noted that one of such lock members is associated with each bracket 1 and has its lowermost end rigidly secured thereto as by rivets or the like 5^a. Each lock member 5 is further provided with a hand-hold portion 5^b.

When the bed is in set-up position the spring-frame member is securely retained between the flange 1^g of the bracket 1 lying thereabove and the shoulder 5^k of the lock member lying there beneath. When it is desired to collapse or fold up the bed, the lock member 5 is manually withdrawn to the position shown in dotted lines, see Fig. 5 of the

drawings, thus permitting the downward movement of the outer edges of the spring frame member and the collapsing thereof.

In Figs. 8 and 9 of the drawings there has been illustrated a modified form of locking means comprising a slide bolt 6 preferably substantially square in cross section and adapted to extend through the aperture 1^k in the bracket 1. The bolt 6 has a hand-hold portion 6^a and a reduced portion 6^b having a bearing in an aperture in a guide 6^c rigidly secured to the bracket 1. A coil spring 6^d is positioned in surrounding relationship with respect to the reduced portion 6^b between the guide 6^c and the bolt proper, and tends to normally urge the bolt inwardly beneath the spring frame member. Manual movement of the hand hold portion 6^a outwardly will result in the withdrawal of the bolt and the compression of the spring. The depth of the guide 6^c is such as to permit the withdrawal of the bolt 6 from beneath the path of the spring frame when it is desired to collapse or fold the bed. Upon the release of the hand hold portion the spring will move the lock bolt inwardly again.

In Figs. 10 and 11 of the drawings there has been illustrated a still further form of lock member comprising a hook-like member 7 having one extremity 7^a thereof pivotally secured within an aperture 1^m within the bracket 1. The opposite extremity of the member 7 is turned inwardly and is designed to be passed through an aperture 3^k formed within an ear 3^b on the spring frame member.

By "set-up" as used herein is meant the positions in which the parts are placed upon the bed being ready for occupancy.

Obviously any other desired type of lock member might be conveniently utilized.

There has thus been described a novel bed of the collapsible or folding type wherein the structure is unitary, that is upon assembly thereof the bed may be changed from set-up to collapsed position at will without any disassociation of parts; a bed having novel provisions adjacent the foot thereof for the reception of a bed-spread or other covering; a bed having a novel spring and novel spring supporting means; a bed which is durable, simple in operation, and may be conveniently manufactured.

The invention having thus been described, what is claimed is:

1. A folding bed including head and foot members, brackets fixed to each of said members at the sides thereof and projecting toward the remaining member, a bed bottom consisting of a plurality of sections hinged to lie in alinement when set up and to fold into substantially vertical and parallel positions when folded, means for pivotally and slidably connecting the ends of said bottom to said brackets, and stop members on the

- brackets against which the bottom engages upon being set up to limit pivotal movement of said bottom sections in one direction, said stop members being further arranged to engage the bottom and prevent sliding movement thereof relative to the brackets upon the bed being set up.
2. A folding bed including head and foot members, brackets fixed to each of said members at the sides thereof and projecting toward the remaining member, a bed bottom consisting of a plurality of sections hinged to lie in alinement when set up and to fold into substantially vertical and parallel positions when folded, means for pivotally and slidably connecting the ends of said bottom to said brackets, stop members on the brackets against which the bottom engages upon being set up to limit pivotal movement of said bottom sections in one direction, said stop members being further arranged to engage the bottom and prevent sliding movement thereof relative to the brackets upon the bed being set up, and spring latches on said brackets engaging the bottom when set up to prevent pivotal movement in the opposite direction.
3. A folding bed including head and foot members, brackets fixed to each of said members at the sides thereof and projecting toward the remaining member, a bed bottom consisting of a plurality of sections hinged to lie in alinement when set up and to fold into substantially vertical and parallel positions when folded, each of said brackets having a horizontally disposed slot adjacent its upper end and having an open branch slot at one end, pins on the sides of said bed bottom in spaced relation to its ends and engaging in said slots to provide pivotal and slideable connection between the brackets and bottom, and lugs projecting from the tops of the brackets and engaging on top of the bottom near the ends thereof whereby to limit pivotal movement of the sections in one direction.
4. A folding bed including head and foot members, brackets fixed to each of said members at the sides thereof and projecting toward the remaining member, a bed bottom consisting of a plurality of sections hinged to lie in alinement when set up and to fold into substantially vertical and parallel positions when folded, each of said brackets having a horizontally disposed slot adjacent its upper end and having an open branch slot at one end, pins on the sides of said bed bottom in spaced relation to its ends and engaging in said slots to provide pivotal and slideable connection between the brackets and bottom, lugs projecting from the tops of the brackets and engaging the top of the bottom near the ends thereof whereby to limit pivotal movement of the sections in one direction, and other lugs projecting laterally from the brackets and engaging the ends of the bottom

upon the pins being positioned in the ends of the slots remote from said branch slots.

5. A folding bed including head and foot members, brackets fixed to each of said members at the sides thereof and projecting toward the remaining member, a bed bottom consisting of a plurality of sections hinged to lie in alinement when set up and to fold into substantially vertical and parallel positions when folded, each of said brackets having a horizontally disposed slot adjacent its upper end and having an open branch slot at one end, pins on the sides of said bed bottom in spaced relation to its ends and engaging in said slots to provide pivotal and slideable connection between the brackets and bottom, lugs projecting from the tops of the brackets and engaging on top of the bottom near the ends thereof whereby to limit pivotal movement of the sections in one direction, and spring latches on said brackets engaging the bottom when set up to prevent pivotal movement in the opposite direction.

6. A folding bed including head and foot members, brackets fixed to each of said members at the sides thereof and projecting toward the remaining member, a bed bottom consisting of a plurality of sections hinged to lie in alinement when set up and to fold into substantially vertical and parallel positions when folded, each of said brackets having a horizontally disposed slot adjacent its upper end and having an open branch slot at one end, pins on the sides of said bed bottom in spaced relation to its ends and engaging in said slots to provide pivotal and slideable connection between the brackets and bottom, lugs projecting from the tops of the brackets and engaging the top of the bottom near the ends thereof whereby to limit pivotal movement of the sections in one direction, other lugs projecting laterally from the brackets and engaging the ends of the bottom upon the pins being positioned in the ends of the slots remote from said branch slots, and spring latches on said brackets engaging the bottom when set up to prevent pivotal movement in the opposite direction.

In testimony whereof I hereunto affix my signature.

WILLIAM CALVANO.
